CIRCUIT MAKE AND BREAK DEVICE

William Foerste, Pelham Manor, N. Y., assignor
to Monarch Neon Sign Co., Newark, N. J., a cor-
poration of New Jersey

Application July 22, 1937, Serial No. 154,984

1 Claim. (Cl. 200—87)

The invention relates to electrical apparatus, more especially to a device for making and breaking electrical circuits of high voltage such, for example, as are met with in the operation of 5 gaseous discharge lamps.

It has for an object the provision of a simple, inexpensive and effective device whereby an electrical circuit is made, or interrupted, electromagnetically and in a manner such that the closure, 10 or interruption, may be caused to occur under relatively high voltage conditions through the control of an independent low-voltage circuit.

In carrying out the invention, a suitable screw-socket or like member is arranged to retain a coil 15 of wire of relatively high resistance and low inductance which is included in circuit with an automatically operating low tension circuit make and break device such, for example, as the well-known thermal interrupters or flashing devices. 20 By this expedient, long life and effective operation of the flasher or the like is insured.

Within the coil is mounted a magnetizable element which is fixedly located therein to be under the influence of the lines of force developed 25 by said coil. There is associated with the said fixed element a further but movable magnetizable element which is positioned relatively thereto so as to be attracted to, or repelled from, said fixed element in being subjected also to the lines 30 of force developed by the said coil. This latter and movable element carries a suitable contact for engagement with a further contact, both of which are located in the circuit to be controlled. It is preferred to include the aforesaid magnetizable elements as well as the circuit controlling contacts within a suitable envelope and evacuate the same with de-gasification of the metals 35 to an extent to prevent ionization.

The nature of the invention, however, will best 40 be understood when described in connection with the accompanying drawing, in which:

Fig. 1 is a front elevation of the novel device, with portion shown in vertical section.

Fig. 2 is an enlarged front elevation of a portion 45 of the device; and Fig. 3 is a side view thereof.

Fig. 4 is a wiring diagram illustrating the electrical connections involved.

Referring to the drawing, 10 designates a base 50 of insulating material such as the usual porcelain base provided with a screw socket 11. A thermal make and break device 12 of well known or special design is mounted on the under side of the base and is included in circuit with the 55 terminals 13 and 14 of the socket whereby an

electric current, either direct or alternating, may be supplied to a screw plug 15 adapted to be retained in said socket in the usual manner, and the current periodically interrupted through the action of the thermally actuated device 12. 5

This plug is provided at its upper portion with a resistance in the nature of an annular winding or coil 20 which affords also a magnetizing field. The said coil is securely retained in the plug and is designed to receive into its central 10 hollow portion 21 one end of an envelope 22 housing contact members adapted to open or close an external circuit connected thereto as will hereinafter be set forth. It is preferred to substantially evacuate the envelope to prevent 15 arcing between the contacts hereinafter described and secure longer life thereof. The evacuation is conducted with degasification of the metals contained in the envelope so that no ionization will take place therein and short-circuiting of the contacts is obviated. It is desirable, also, to make the coil 20 of low inductance and of relatively high resistance to reduce to a 20 minimum deterioration of the contacts of the thermal make and break device 12. 25

At the end of the envelope which fits into the coil there is provided a fixed magnetizable element 25 in the nature of a strip of iron or steel held in place, for example, by means of a stiff wire 26 carried by a bead 27 resting against the 30 wall of the envelope which may be of glass. The said envelope is introduced into the said coil 20 to an extent sufficient to cause the element 25 to lie within the field of said coil and become magnetized when the coil is energized. There is associated with said element 25 a further magnetizable element 28 which is mounted within the envelope 22 in such a manner as to be movable relatively to the fixed element 25. For example, it may be suspended by a flexible connection as the spring element 29 from an insulation strip 30 of mica or the like positioned in the envelope. The natural period of vibration of this element will, of course, be made sufficiently different from the frequency of the magnetizing current, when an alternating current is utilized for this purpose, so that the said element will not be objectionably affected thereby. 40 45

In case it is desired to have element 28 attracted to the element 25 when the latter is 50 magnetized, the said element 28 will be displaced along its magnetic axis to an extent sufficient only to juxtapose its one pole with reference to a pole of opposite polarity of the element 25. Should the control be effected by a repelling ac- 55

tion between the two elements, element 28 will be displaced to an extent sufficient to bring both of its poles opposite corresponding poles of the element 25.

- 5 The movable element 28 carries a contact 31 which is normally held, in the embodiment shown, to a further and fixed contact 32 through the action of the spring 29; and is separated therefrom only when coil 20 is energized, magnetizing thereby both of the elements 25 and 28 and causing the latter to be attracted to the former. It will be understood, of course, that the action may be reversed and the contacts closed on energization of the said coil.
- 10 Leads 33 and 34 connected to the respective contacts 31 and 32 connect with suitable terminals 35 and 36, respectively, located exteriorly of the envelope for convenient connection to an external circuit to be controlled by the novel device. For example, the device may be included in a high tension circuit as the secondary circuit 40, Fig. 4, of a gaseous discharge lamp system embodying a plurality of lamps 41 and 42. The former lamp may be connected directly across
- 15 the secondary 43 of a transformer and the latter in series therewith, as shown, in which case lamp 41 is to have a higher ionization voltage than the lamp 42. In operation, as the circuit for the lamps is opened at the contacts 31 and
- 20 32, lamp 41 will become energized; and, when the circuit is closed, the lamp 42 alone will be energized. Thus an alternate illumination of the two
- 25
- 30

lamps will be effected, as the low tension circuit controlled by the thermally actuated device 12 is made and broken to control the energization of the coil 20, and without any direct connection between the low tension and the high tension circuits. 5

I claim:

A contact device, comprising an elongated envelope, a contact unit for mounting therein and including a single, non-magnetic support resting 10 along its sides against the envelope wall, together with a stiff wire extension projecting from one end of the support and carrying a bead resting against a further and opposite wall portion of the envelope, a magnetizable element fixed at 15 said end of the support, said envelope being adapted to fit within a magnetizing coil to position said magnetizable element for magnetization thereby, a second magnetizable element and a resilient connection between the same and the 20 support, said element being adapted to swing in juxtaposition to the first-named element and carrying a contact member, and a further and fixed contact member attached to the support and located in juxtaposition to the swingable 25 contact member, the latter being normally biased for engagement therewith through its said resilient connection to the support, together with terminal means secured to the support at its opposite end for suspending the said support from 30 the envelope.

WILLIAM FOERSTE.
